Term of patent 14 years

(Cl. D81—25)

FIG. 1

FIG. 2

FIG. 3

FIG. 4

FIG. 1 is a front elevational view of a smoke exhausting hood or the like embodying our new design.

FIG. 2 is a top plan view of the same.

FIG. 3 is a side elevational view of the same.

FIG. 4 is an enlarged, vertical, sectional view looking in the direction of line 4—4 on FIG. 1.

The stippled area of the panel in FIG. 1 indicates contrast. The undisclosed side is substantially the same in

appearance as the side shown. The dominant features of our design reside in the portions shown in full lines.

We claim:

The ornamental design for a smoke exhausting hood or the like, as shown and described.
